UNITED STATES PATENT OFFICE

CARL ROBERT BLUM, OF BERLIN-SCHONEBERG, GERMANY

METHOD AND APPARATUS FOR RECORDING SERIES OF MOTION

Application filed September 27, 1929, Serial No. 395,722, and in Germany September 1, 1926.

All series of motion in the art of music are governed by laws called rhythm and metrics. These laws may be coupled more or less strictly and may be subject to modulation. By metric, such a series of motion ought strictly to be understood whose periodic succession would be entirely uniform. Such series of motion however are very rare and in the art the motions will change freely within the limits of the existing laws. For that reason the metronom by Mälzl has proved useless.

The present invention discloses means for reproducing the series of motion in the same manner as they occurred originally. In order to avoid any mistake caused by the alternative use of the terms "rhythm" and "metric" it may be mentioned, that in order to be able to record or fix and reproduce a series of motions true to nature, it is necessary to obtain the following three data:

- (1) The commencement of a portion or unit of time of a series of motion must be determined,
- (2) The duration of the portion of time, and
- (3) Whether the individual portion of time is accentuated or not.

When these data are obtained, the reproduction can be carried out according to the original of the series of motion. For that purpose the individual portions are recorded upon continuous bands, but it must be noted that during their manufacture and reproduction the speed of reeling of said bands must always be the same.

Even if the band is reeled off to its entire length at a varying tempo, the original rhythm will be maintained, for the relative period between the individual elements of motion will be fixed. After said bands have been produced it is possible to cause them to pass a stationary point or mark of reference in order to utilize the signs recorded thereon and to read the original rhythm true to nature and to reproduce it. As the rhythm can be reproduced accurately by means of such bands, they may be referred to herein-after as "rhythm-bands".

Previous to more fully disclosing the subject matter of the invention, an example in

music may be mentioned, although according to this invention any series of motion may be recorded. However, the novel features might become more obvious by way of some musical examples. For instance, an orchestra is producing the music at the performance in a moving picture show, which orchestra is conducted by the bandmaster in such a way, that the tunes will sound exactly at that moment, in which the corresponding note upon the rhythmband being reeled off simultaneously with the film, passes a stationary point or mark of reference. It is immaterial whether one series of motion per se or rhythmically coupled series of motion are concerned.

Fixing these series of motion according to the invention is carried out in such a manner, that upon a band according to which the rhythmband is produced, the primary accents are marked in the upper column by longer or shorter dashes, and the secondary accents in the lower system of two rows in such a manner, that the three conditions referred to above are discernible simultaneously and unambiguously.

The apparatus described hereinafter in principle is adapted both for the reproduction of rhythmbands and also for the manufacture thereof. For the manufacture merely a removable writing device for marking the bands will be required.

In the drawings several embodiments of the apparatus according to the invention are shown by way of example.

Figure 1 is a perspective view of the apparatus which may be called "rhythmonom",

Figure 2 is a similar view with lid opened;

Figure 3 is a cross-section, and

Figure 4 a top plan view of the mechanism.

Figure 5 is a plan of the scales of a "tempo-meter".

Figures 6 to 8 show various form of marking the band.

Figures 9a and 9b are details in section and plan respectively.

Figures 10a and 10b are some further details of the same apparatus.

Figures 11a and 11b show further views of the rhythmband.

Figure 12 is a diagrammatic view of the note writing device for the said band connected with the keyboard of a piano.

Figure 13 is an enlarged view of the controlling device.

Figure 14 shows a variable transmission gear, and

Figure 15 is a diagrammatic view of the rhythm band and tone band.

In the first place an embodiment of the reproducing apparatus is shown by way of example in Figures 1 to 4 and it is assumed that finished bands are already available.

As will be particularly noted from Figures 3 and 4 the rhythmband 1 passes from the reel 2 by way of the guiding roller 3 through the window 4 and over the feeding drum 5 to the winding up reel 6. On the shaft of the reel 2 is mounted a wooden core 7 and the reel 6 is provided with a wooden core 8. The axis 9 of the reel 6 projects beyond the core 8 and is provided with a milled knob 10. A funnel-shaped recess 11 in the cover 12 permits the actuation of the button 10 even if said cover or lid 12 is closed. The said button 10 serves for adjusting the rhythmband. The lower portion of the axis 9 is journaled in the bearing 13 and carries on its lower end the rope-pully 14.

Upon the inclined mounting plate 15 is secured by means of screw-bolts 16 a motor 17. This latter carries on the upper end of its shaft a gear wheel 18 meshing with the gear wheel 19.

The gear wheel 19 and the rope pulley 20 are fixed to a shaft 21, rotating in the bearing 22 and carrying at its upper end the feeding drum 5. Over the rope pulleys 20 and 14 passes a cord 23. In addition there is mounted on the plate 15 in the rear of the band window 4 a soffit lamp 24.

The rhythmband passing through the window 4 being lit by the lamp 24 can be inspected through the funnel 25 when the cover 12 is closed, how it passes the indicator or reference mark 27 after the latter has been adjusted by means of the rod 26.

Within the casing 28 on the front wall there is secured a regulating resistance 29 adapted to be actuated by means of the turn-button 30 and the adjustment of which can be read off each time from the annular scale 31. The number of revolutions of the driving motor 17 is controlled by said resistance 29, in case the apparatus (rhythmonum) is driven alone. The connection leads are not shown for the sake of keeping the drawings clear. If it is desired, however, to effect a synchronous connection, for instance with an apparatus for the reproduction of moving pictures, the said resistance 29 may serve for the control of the number of revolutions of the driving motor for the cinematographic

apparatus and the motor 17 is controlled in synchronism with said cinematographic apparatus. For that purpose a motor of special construction for instance an electric motor, must be used whose motor field is controlled by means of a turning switch mounted upon a turning part of the said cinematographic apparatus and effecting a series of circuits with the motor in the rhythmonum.

For synchronous operation of the cinematographic apparatus and the rhythmonum there is provided on the front wall of the box 28 a combined scale 32 of a tachometer for controlling the velocity of the band 1. As will be seen from the diagrammatic view in Figure 5 two scales 33 and 34 are provided—particularly for the control of the synchronous reeling off of the film and the rhythmband—which scales can be adjusted with relation to, i. e., moved toward and from, one another, one of which will indicate the music tempo for different moving picture frequencies, for instance, by per cents of the recording time, and the other one will indicate the moving picture frequencies proper.

If for instance, the rhythmband was recorded with a moving picture frequency of "18" with a musical time of "72", the pointer 35 is placed on the graduation line "18" of the scale 34 for the picture frequency (see Figure 5). In order to bring the musical time each time in relation with the moving picture frequency, the figure "100" of the scale belonging to the moving picture frequency "18" on the tempo scale 33 is adjusted to the thread of the pointer 35. Then the controller 30 of the film and noteband driving device is adjusted in such a manner, that the pointer 36 of the tachometer coincides with the direction of the adjusting mark 35, that is to say it will coincide with the graduation line "18" of the frequency scale 34 and with the figure "100" of the tempo scale of music for the frequency "18", while the musical time of the reproduction amounts to 100 per cent of the music tempo in existence during the recording operation.

If now an acceleration of the tempo is desired, of say 20 per cent, the regulator 30 common to the driving devices is to be adjusted in such a manner, that the pointer 36 of the tachometer will cover the numeral "120" on the same scale for the music tempo, while it will at the same time indicate the new moving picture frequency "21.6". The numeral "120" in this case will indicate the acceleration of the original time "72" in per cents, which now will amount to $72 \times 1.2 = 86.4$.

If the rhythmband is not to be brought into relation with the running film, the figures on the graduation need not be changed, since the indications of the picture frequency implicitly also contain the velocities of the rhythmband.

The ratio of transmission of the gear wheels

18 and 19 is suitably such, that the rhythm-band will be reeled off at a speed which will permit the marking of the band as well as the reading during the reproduction. For bringing the rhythm-band into relation with the picture-film it is preferable to choose even numbers in the proportion of the speed of the bands from about 1:8. It is also of advantage to be able to change the proportion 5 of the speed of reeling off the rhythm-band and the film by means of a variable transmission device.

10 The manufacture of the rhythm-band can be effected on the same apparatus by using a removable device and is as follows:

15 In the first line a blank band (not shown in the drawings) is provided which will pass through the rhythmonom in the same manner as during the reproduction above described.

20 By means of this removable device, called "rhythmograph" two lines of markings or characters are produced on the moving blank band, as shown in Figure 6. The primary accents are marked according to the invention

25 in the upper column and the secondary accents in the lower column in such a manner that the association of the series of tones can be made out at the same time and unambiguously. By means of this original "rhythmogram" the rhythm-band proper may obtained,

30 which will contain over a certain proportion of length on a band printed with music lines, the customary notes, and after finishing the band will show the appearance illustrated in

35 Figure 7. According to the position of the primary accents the bar-lines and laterally thereof in continuation the bar-numbers (143, 144 and so on) are entered subsequently. If a musically bound text (song, recitation or 40 the like) is concerned, the distribution of the syllables follows from the musical rhythm. A band of that type is shown in Figure 8.

The manufacture of pure bands for speech is carried out in the following manner:

45 The original rhythmogram according to Figure 6 is preferably again transferred to a second band in a definite proportion of length.

50 With a rhythmogram of speech corresponding to the music rhythmogram according to Figure 6 the marks or signs or characters may be put on in such a manner that the beginning of a sentence or portion of a sentence is designated by two superposed marks, while the final syllables of a portion of a sentence are rendered discernible by dashes, the length of which is determined by the actual duration of the sounding.

55 It is very suitable for reading the finished band for speech, that is for reproduction, to provide said band according to Figure 8 with transverse lines in order to ensure the reading while the band passes the mark of reference. It is advisable to serially number

these "talking bars" too (160, 161, 162 and so on).

The production of various kinds of rhythm-bands is dependent on two technical assumptions:

(1) The band must be moved uniformly, and

(2) It must be provided with written characters.

The first supposition is fulfilled by the reproducing apparatus, the rhythmonom, of the type described above, which is also adapted for reeling off the band during the reproduction. The second supposition is fulfilled in that by means of a removable device the band running out is provided with written characters. Said removable device is called "rhythmograph" as already mentioned.

75 Figures 9a, 9b and 10a, 10b show by way of example an embodiment of said rhythmograph. It consists of two parts electrically connected by means of a cable having three veins.

80 One of these parts shown in elevation in Figure 9a and in plan in Figure 9b is attached to the rhythmonom in front of the funnel 25 by means of screws. It consists for instance of a frame 37 accommodating both the solenoids 38 and 39. Inside of these latter is arranged a small iron tube 40 and 41 each above a pin 42, 43 each, which may consist of aluminium. The two pins 42, 43 are held in the position shown in the drawings by means of a draw-spring 78 and 79 each. The pins 42, 43 carry on their left extremity a small disc 44, 45 each which possess a writing point 46 and 47 respectively. The frame 37 is secured to the plate 48, which latter can be connected to the rhythmonom by means of grooved screws 49. The ledge 50 serves for guiding the pins 42 and 43. In front of the points 46 and 47 an inked ribbon 51 is passed by way of the guiding rollers 52 from the ribbon drum 53 to the roller 54. The ribbon drum 53 is mounted on an axle 55, carried by the arm 56 secured to the frame 37. The ribbon-drum 54 however, is mounted on a rotating axle 58 carried in a bracket 57 secured to the frame 37. At the lower end of said axle is mounted a ratchet-wheel 59 into which 115 engages a pawl 60. On the lid 61 of a pot-shaped magnet 62 is arranged a second pawl 63, which will advance the ratchet-wheel 59 clock-wise each time the pot-shaped magnet is energized, causing the inked ribbon to be 120 advanced so that a fresh portion thereof is placed in front of the pins 46 and 47.

125 The other portion of the rhythmograph by means of which the part described above is actuated, is shown in Figure 10a in elevation and in Figure 10b in plan. It consists of the base-plate 64 connected by means of a side-piece 66 with the cover-plate 65. Round the axle 67 swing two two-armed levers 68 and 69, carrying at its extremity a key, 130

and 71 respectively. At their opposite extremities they carry each a resilient contact member 72 and 73 respectively, each confronted by contact members 74 and 75 respectively, fixed to the cover-plate 65.

On pressing down the key 71 the contacts 73 and 75 engage one another and close the circuit, in which the solenoid 39 is situated. This will cause the small iron tube 41 together with the pin 43 and the point 47 to be forced against the inked ribbon 51, and the lower point 47 will produce on the blank band 76 passing close in front of said inked ribbon, a shorter or longer mark in accordance with the duration of the contacting action. If the key 71 is released it will return into its position of rest under the action of the leaf-spring 77. In the same way the lower pin 43 will return to its initial position under the action of the draw-spring 78.

If the key 70 is depressed a second circuit will be closed in a corresponding manner, and as the upper solenoid 38 is situated in said circuit, the upper point 46 will be pressed against the inked ribbon 51.

The pot-shaped magnet 62 is inserted into one of these two circuits. If said circuit is closed, the advance of the ratchet-wheel 59 will also shift the inked ribbon 51.

The mode of operation of this band writing device (rhythmograph) now is such that a musician is depressing simultaneously with a musical or pictorial performance both keys 70 and 71 in the rhythm of the said performance while the apparatus is writing the primary and secondary accents on different lines on said band. It is not absolutely necessary that original music be concerned as the rhythmogram may be produced while recorded music is being played, as, for instance, from a phonogram or the like. In this instance the band illustrated in Figure 6 will also be obtained, in which the signs or marks are entered on two superposed lines, as this is the case according to this invention.

Under circumstances, especially if some improvised music is concerned it is of importance not only to record the rhythm and metre but also the melody.

According to the invention this is effected in that on the continuously moving blank band the succeeding individual characteristic notes are marked at a distance from each other, corresponding to the periodic course, for instance by means of full round heads of notes. Accents are marked by additional signs such as 106 of Figure 11a.

As follows from Figure 11a the round heads of the notes are at once brought into relationship with a staff, so that they will at the same time mark the pitch proper.

As the distance of the individual musical types from each other will indicate their accurate time-value, the marking of the time-value customary with the known writing of

music, that is to say, the discrimination by hollow and full round heads of notes and the provision of different mensural hooks and so on can be dispensed with.

For carrying this method into effect any suitable device, for instance a special type-writing machine may be used, whose types consists of a short staff of five lines showing each in said staff or on auxiliary lines above or below, a head of a note in the usual manner. For the marking of enharmonical exchanges one or more levers according to the known reversing levers in type-writing machines may be employed. If it is desired to discriminate graphically for instance the equally sounding tunes "c sharp" (c #) and "d flat" (d b), as such is necessary in the orthography of musics, this can be done by manipulating the lever for instance in such a manner, that for tunes with the # accidental the said lever is raised, and for tunes having the b accidental is depressed, while its central position will correspond to tunes having no such accidentals. With the keys of this writing device there may be connected in addition sounding bodies or elements, such as tuned discs, pipes or the like, so that the rhythmical records may be simultaneously controlled melodically. It is also possible to connect a key-instrument or the like played during the recording operation, with such writing device. Or the writing device may be connected for instance pneumatically or electrically, so that the music is automatically fixed during the performance.

The band represented in Figure 11a is completed to advantage, in that by means of an inked roller the note lines or the staff are produced continuously. A second staff or a plurality thereof may be provided at the same time on the band as this is represented in Figure 11b.

Figure 12 illustrates diagrammatically such a music writing device connected with the keyboard of a piano or the like. On depressing the key 79 of the piano the wheel 80 carrying the types will effect the inscription upon the blank band 76. By the key 79 the lever 81 is turned about its fulcrum and in consequence the toothed segment 82 secured to its extremity will rotate the gear wheel 83. The latter is suitably connected with a bevel wheel 84, meshing with a bevel gear-wheel 85 mounted on the same axle 86 as the type wheel 80. By correspondingly dimensioning the toothed segment 82 and the gear wheels, the type-carrying wheel is rotated to such an extent only, as such will correspond to the note allotted to the key 79. It is obvious that the lever system of all keys of the piano will actuate the same type-wheel. It is not necessary to illustrate the total arrangement in all its details, since such arrangements are well known in type-writing machines.

After the type-carrying wheel has been placed in the proper position in front of the blank band 76, the type wheel must be caused by means of the levers 87, 88 and 89 to beat against the said blank band and print the corresponding type. After the printing the type wheel is returned into its inoperative position by means of the spring 90. In order to be able, however, to discriminate the 10 flat equally sounding tunes "c sharp" (c $\sharp$) and "d flat" (d $\flat$) graphically, it is necessary to provide a reversing key suitably pedal operated, by which the type wheel is raised and it will then print "c sharp" (c $\sharp$) in lieu of 15 "d flat" (d $\flat$).

By means of a special arrangement, which likewise may suitably be pedal-operated, those notes are marked, which are accentuated. A writing pencil 105 will produce on 20 the band 76 dots, which for instance may lie below the writing in music and which on the band represented in Figure 11a are denoted by 106. Between the pedal 107 and the pencil 105 various levers are provided for the transmission of the motion. The lever 108 is connected with lever 107 so that by the upper end of the former the rod 109 may be displaced towards the left side. On account of this 25 displacement the lever 110 is turned and, by means of the lever 111 the lever 105 is actuated.

The tacit supposition of the aforesaid is that the rhythmband is caused to be reeled off both during the production as well as during 30 the reproduction at an absolutely uniform speed.

An astronomic clock is best suited for this purpose namely in such a manner, that the driving motor for the shifting drum of the 40 rhythmband is controlled by said clock by interposing suitable mechanical or electrical elements.

If the production of a phonogram (sound- 45 ing disc, steel wire or the like) is carried out in the orchestral pitch (amplitude 435) the phonographic reproduction will also accurately sound in said orchestral pitch after the velocity of the appertaining rhythmband has been adjusted to that of the production. If 50 however, a transposition to another pitch is desired, this is effected by means of a rhythmband controlled by an astronomical clock in such a manner, that either the speed of the clock is changed by adjusting its regulating 55 lever by means of a specially gauged scale, or that between the driving motor and the shifting drum of the rhythmband a transmission gear with constantly changeable ratio of transmission is interposed and adjusted correspondingly. In this latter instance too it 60 is suitable to pass the adjusting lever past a specially gauged scale.

Figure 13 shows diagrammatically the said controlling lever 91 of the clock-work and the 65 appertaining scale 92, the graduations of

which will indicate into which tone the orchestral pitch α is changed to a high or low tone, when the controlling lever is covering them.

Figure 14 shows diagrammatically by way of example a transmission gear with constantly changeable ratio of transmission. 93 represents a small bevel-wheel whose axis represents the prolongation of the driving motor for the feeding drum 95 of the band. 75 94 is a larger bevel-wheel to the upwards extending extremity of its shaft the shifting drum 95 for the transport of the band is wedged. The ratio of transmission is changed by the displacement of the leather belt 96. 80 Such displacement of the leather belt 96 is effected by means of a fork 97 mounted at the end of a two-armed lever 98. The adjustment of the latter is effected through the turn-button 99 and the scale 92, whose gauge 85 is equivalent to the scale represented in Figure 13.

In the following some modes of application of the rhythmonom for utilizing the finished rhythmband are described.

In the first line the rhythmonom is excellently adapted for studying musics. If the pupil causes a rhythm-noteband to pass past the reference mark of the rhythmonom, he is able to unravel the most intricate rhythmic connections at once. Up to the present a reliable analysis of the rhythmics was impossible merely with the aid of the usual note signs, in spite of the application of the metronom. It is of great advantage, that the pupil 100 is enabled to study the original rhythm not only in the original tempo, but in any desired acceleration or retardation. It is immaterial whether instrumental or vocal music or both kinds are concerned. Especially for the difficult analysis of talking song (recitation and melodrama) the use of the rhythmonom is 105 indispensable.

The work of the management of theatres is also greatly facilitated in that, for the 110 study of the parts and the ensembles the rhythmonom will produce a uniform musical guide to go by, which is especially advantageous with new productions.

For directing separate tone bodies any required number of rhythmonoms can be connected, either mechanically, for instance, for a modern stringed quartette or electrically over a distance, for instance in the case of locally separated orchestras and collaborating massed choirs, which are not clearly within the comprehending range of vision of the band-master.

Up to the present it was impossible to 125 utilize artistically to their full extent automatic pianos, organs or the like, even when using so-called artist's rollers, for the accompaniment of soloists, ensemble-music and so on. Only after the building-in of the rhythmonom into such instruments or 130

through coupling them with said rhythmonom it is possible for anybody to bring at once by means of the rhythmband passing in synchronism with the artist's roller the reference mark the music reproduced automatically into rhythmically absolute conformity with music produced naturally. This mode of application is illustrated in Figure 15. The roller 100 paying out and the roller 101 taking in the music band 102 of an automatic key instrument (pianola) are represented diagrammatically.

On the shaft of the reel 101 there is provided a bevel gear wheel 103 meshing with a bevel wheel 104, which engages the lower end of the axis of the transporting drum 105 of the rhythmonom. Owing to this arrangement the rhythmband will pass in the manner described above the reference mark simultaneously with the running out of the music band. Obviously there may be a difference in the length between the rhythmband and the music band of the key instrument. In this instance too, there is provided a means for students of music, to make out simultaneously with the reproduction of the music the inner relation of the musical construction, aided by the rhythm-noteband.

If it is desired when studying parts or scores, not only to watch the rhythm-noteband pass the reference mark, but to hear simultaneously and in synchronism with it the appertaining music, the rhythmonom is connected with one of the known sound reproducing apparatus. It is immaterial whether or not an apparatus actuated by needle-, light- or magnet-tone is concerned. Such connection may be direct, in that in the rhythmonom proper the motion of the rhythm-noteband and that of the sound carrier is derived from one and the same shaft, driven by a motor. However, the rhythmonom and the sound reproducing apparatus may also be arranged in separate localities. In this instance their connection is effected either mechanically, perhaps by means of a flexible shaft, or electrically by employing a synchronizing device.

The rhythmonom may be utilized in a similar manner for all kinds of studies of speech, that is to say the rhythmband proper alone or in connection with phonograms.

Per se the said rhythmband will facilitate young actors or public speakers the study of the rhythm of speech and in addition it will also facilitate the appropriation of the technic of speech.

Connected with phonograms running out in synchronism with the rhythmband it affords the possibility to study whole rôles in the conception of famous actors both as regards in rhythmical and melodical respect of speech. The study and the reproduction of melodramas is in particular materially facilitated. For that reason the rhythmonom

is particularly adapted as a means for learning foreign languages, since it will visually demonstrate in synchronism with the living sound of a word, transferred by the talking machine, also the living picture of the word passing a reference mark.

If separate instruction is concerned, it will be sufficient to use an apparatus in which a band with inscriptions is running out in synchronism with the carrier of the phonogram in the talking machine in such a manner, that the lettering of the words or notes on the band may be inspected directly. It is immaterial whether the carrying element of the phonogram is a disc or roller, a band or wire or the like.

For the instruction of groups of students an apparatus with moving letters of such type may be employed, which comprises a mat or opaque window pane or screen, upon which the moving letters are projected.

When teaching whole classes of pupils it is of advantage to employ an apparatus with moving letters, which will admit of the said moving letters being projected upon a special screen or wall. Under circumstances it may be of advantage to proceed as follows: An apparatus for taking cinematographic films is connected in synchronism with an apparatus with moving letters for direct inspection and the moving letters are then taken cinematographically. During the lesson a cinematographic projecting device is connected in synchronism with the talking machine, in order to simultaneously render tangible to the pupils in a lifelike manner the sound and the letters of the word during reproduction. And it is immaterial per se again, whether or not the talking machine and the moving letters are employed separately or in combination. If the carrier of the phonogram is a band, it is possible that the latter may form a unit with the picture band of the moving letters. In this instance the synchronous run of the phonogram and the running letters is given at once. As the moving letters will require but a comparatively narrow band of the picture field at the disposal, it is recommendable in order to stimulate the lesson or the instructions, to utilize the space available yet for the provision of a picture of the situation adapted each time to the subject of the lesson.

According to the invention such picture may be a moving one or a diapositive; under circumstances the technic of tricks may also be employed.

A vast territory for the utilization of the rhythmonom is the theatre.

Here it is used to advantage for instance in such a manner, that a rhythmband running out in a main apparatus will control a plurality of bands in auxiliary apparatus connected in parallel. These may be alike or different, but they must be co-ordinated

in rhythmical respect. If for instance, the performance of an opera is concerned, the main apparatus is operated by an assistant bandmaster in such a manner, that the notes passing the reference mark will correspond to the music sounding in the usual manner according to the direction of the head bandmaster.

One of the auxiliary apparatus for instance may serve for accurately indicating the instant at which certain light or sound sensations must be produced on the stage. But it may also be adapted in such a manner that the production of such effects or sensations is obtained automatically. This is attained in that the rhythmband is caused to close contacts at certain points of its run, which are connected to corresponding electro-magnetically acting releasing relays.

Other auxiliary apparatus are arranged in all the actor's dressing rooms, refreshment rooms and so on, enabling the artists to be informed at any time about the state of the performance by means of the rhythmband running off and to appear on the scene in time.

Further it is advantageous to direct choirs, small orchestras and so on, which are to sound behind the stage, according to a rhythm noteband running out in one of the auxiliary apparatus past a reference mark. As experience shows, such choirs or small orchestras frequently commence too early or too late or very easily get out of time with the main orchestra. This sensitive source of trouble is positively avoided by the use of a rhythmonom.

The rhythmonom however, can also replace the prompter. For that purpose, for instance, the opening of the prompter's box is provided with a projecting screen, upon which is projected sufficiently enlarged the lettering of the rhythmband running out.

Similar apparatus, in which upon an opaque pane the whole projected score passes past a reference mark, may be made available to the critics, students of music and other interested parties in the auditorium, which is particularly recommendable, if some novel plays are performed.

In theatres the rhythmonom may also be employed in connection with cinematographic projection, if it is desired to combine stage and film sceneries.

If, finally, it is desired to connect natural productions of tone in the theatre with artificial tones, the rhythmonom may be used to advantage as controlling element. It is immaterial whether automatic musical instruments or phonographically acting devices are to be connected.

The modes of application referred to in the premises will in no way exhaust the possibilities of application of the apparatus according to the invention.

It is surely to be expected that the rhythmonom and the rhythmband will also be utilized for other purposes, for instance in criminal cases for recording the personal rhythm of speech with the object in view of identifying suspected persons.

I claim:

1. The method of recording the duration, spacing and accentuation of motions which consists in moving a band past a fixed point at uniform speed, causing the motions to be recorded to effect markings on the band corresponding in duration and spacing with the motions, the recording of the unaccented motions being effected in one line on said band and the recording of the accented motions being effected in a second line spaced transversely of the band from the first line.

2. The method of recording the duration, spacing and accentuation of musical notes which consists in moving a band longitudinally past a fixed point at uniform speed, causing musical notes desired to be recorded to produce markings on the band varying in length directly as the extent of duration in time of such notes and varying in spacing longitudinally of the band directly as the extent of duration in time between successive notes with unaccented notes indicated in one line of markings and accented notes indicated in a second line of markings offset laterally of the band from the first line.

3. In an apparatus for recording the extent of duration, spacing and accentuation of musical notes and the like, a recording band, means for feeding said band at uniform speed past a fixed point, a band marking device located at the fixed point and including a pair of marking elements, and means to operate said elements in accordance with the duration and spacing of the notes to be recorded, said means being arranged to operate one of the elements solely during the recording of accented notes.

4. In an apparatus for recording the extent of duration, spacing and accentuation of musical notes and the like, a recording band, means for feeding said band at uniform speed past a fixed point, a band marking device located at the fixed point and including a pair of marking elements, and means to operate said elements in accordance with the duration and spacing of the notes to be recorded, said means being arranged to operate one of the elements solely during the recording of accented notes and to operate the other element solely during the recording of unaccented notes.

5. In an apparatus for recording the extent of duration, spacing and accentuation of musical notes and the like, a recording band, means for feeding said band at uniform speed past a fixed point, a band marking device located at the fixed point and including a pair of marking elements, and

- means to operate said elements in accordance with the duration and spacing of the notes to be recorded, said means being arranged to operate one of the elements solely during the recording of the accented notes, said elements being spaced transversely of the band and alined with the fixed point whereby the elements produce markings on a pair of lines similarly spaced transversely of the band.
6. In an apparatus for recording the extent of duration, spacing and accentuation of musical notes and the like, a recording band, means for feeding said band at uniform speed past a fixed point, a band marking device located at the fixed point and including a pair of marking elements, and means to operate said elements in accordance with the duration and spacing of the notes to be recorded, said means being arranged to operate one of the elements solely during the recording of accented notes and to operate the other element solely during the recording of unaccented notes, said elements being spaced transversely of the band and alined with the fixed point whereby the elements produce markings on a pair of lines similarly spaced transversely of the band.

In testimony whereof I have affixed my
30 signature.

CARL ROBERT BLUM.
